UNITED STATES PATENT OFFICE.

PETER F. JOHNSON AND ARTHUR L. FIRPO, OF RUTHERFORD, CALIFORNIA.

DRY CONCENTRATOR.

1,333,922.

Specification of Letters Patent. Patented Mar. 16, 1920.

Application filed August 8, 1917. Serial No. 185,066.

To all whom it may concern:

Be it known that we, PETER F. JOHNSON and ARTHUR L. FIRPO, citizens of the United States, residing at Rutherford, in the county 5 of Napa, State of California, have invented a new and useful Dry Concentrator, of which the following is a specification in such full and clear terms as will enable those skilled in the art to construct and use the 10 same.

This invention relates to a dry concentrator for the removal from ore of heavy materials.

An object of the invention is to provide 15 means whereby a reciprocating table may be used for treating the ore, and which may be adjusted to different grades as may be required by the ore under treatment.

This concentrator is intended for the purpose 20 of handling finely divided or comminuted ores containing particles of widely different specific gravities and for the collection of the heaviest of those particles.

The method of operation of the table is to 25 provide a surface from which will issue air under a sufficient pressure to gently disturb or agitate the ore mass, while at the same time, the ore mass is mechanically agitated in the length of the table, the result of which 30 is to cause the heavy particles to settle to the bottom of the mass, while the lighter particles representing the waste will work to the top and be discharged over the table surface.

In the present invention, advantage of 35 this action of air and mechanical movement upon a mass of finely divided ore is taken to produce a continuous separating action in which the heavy particles will be delivered to a series of concentrating hoppers, while 40 the lighter particles are discharged from the table as tailings.

Other objects of the invention will appear as the description proceeds.

An embodiment of the invention is shown 45 in the drawings in which the same reference numeral is applied to the same portion throughout, but we are aware that there may be modifications thereof.

Figure 1 is a side elevation partly in section of the complete concentrator,

Fig. 2 is an end elevation of the lower end of the concentrator looking from the right Fig. 1,

Fig. 3 is a plan view of the concentrator, 55 and

Fig. 4 is a side elevation of one of the

posts on which the concentrator adjusting mechanism is mounted.

The concentrator is mounted upon a base frame having side pieces 1 and 2 and connected together with suitable transverse end pieces 3, 3' and 4, while there is another longitudinally extending stringer 5 supported on posts 6 and 7, for the support of the concentrate receiving troughs or launders 8 to 14 inclusive.

The concentrator table is supported on four posts 15 to 18 inclusive and is reciprocated by means of a pitman 19 extending around an eccentric 20 on the shaft 21, the latter shaft being mounted in suitable journal boxes 22, 23, carried by the posts 15 and 16 respectively. The shaft carries pulleys 24, 25, one larger than the other to drive it and the fan.

The posts have suitable braces 26 to 29 inclusive extending to the horizontal sills of the machine. The posts 17, 18 have two inwardly extending brackets 31, 32, connected therewith at their upper ends, which 35 brackets each support a ball as indicated at 33, 34, oppositely placed brackets 35, 36 being carried by the table for the support thereof. The upper end of the table has two brackets 37, 38, extending laterally 40 therefrom over a pair of brackets 39, 40, which are supported on the screws 41, 42 respectively. The screws are revoluble in the posts and are secured at their upper ends in plates 15' and 16' on the top of the posts 45 15, 16. Each of the screws 41, 42 is provided with a bevel wheel 43 at its lower end and said bevel wheels are in mesh with bevel wheels 44, 45 on a shaft 46, which carries a hand wheel 47 to enable the operator to adjust the elevation and grade of the concentrator table.

The brackets 39 and 40 each have a roller or ball 48 thereon upon which the brackets 37, 38 rest, and upon which the table reciprocates.

The table consists of two relatively deep side members 49, 50, with a hopper 51 at the upper end thereof.

The table surface consists of a plurality of 105 flat plates 52 in such numbers as may be desirable for the particular ore to be treated, one plate being set slightly above the other to permit the escape of air between the same into and through the body of ore 110 passing over the table.

The table has concentrate receiving hop-

pers 53 to 59 inclusive, each of which has a small spout opening into one of the concentrate launders 8 to 14 inclusive.

It will be observed that the plates making up the table surface, see Fig. 3, are of different widths, the object of this being to provide many or few air escape openings as the particular ore under treatment may require, and to provide a wider baffle plate at 10 each concentrate collecting roll, said plate having an incline up which the ore must be worked by the air to reach the next air box.

At three places in the length of the table, there are collecting rollers 60, 61 and 62, 15 which extend across the table below openings formed by one of the riffle plates 52 and the baffle plates 52', and said rollers are slowly rotated to carry any heavy material that may be deposited thereon into the hoppers 55, 57 and 59. The shafts of those rollers each have a gear wheel thereon as illustrated at 63, 64 and 65, said gears being respectively in mesh with the gears 66, 67 and 68 adjacent them, and which gears are 20 rigidly connected with the sprocket gears 69, 70, 71. A chain 72 passes over and around these sprocket gears and a roller 73 holds said chain in contact with the sprocket wheel 70, for a purpose presently to be explained.

30 The gear 70 has an arm 74 loosely mounted upon its shaft, and said arm carries a pawl 75 which engages the inside of the flange of the wheel 70 and rotates it when the arm 74 strikes the post 77. The spring 78 serves 35 to hold the arm 74 in engagement with the post in order to cause it to rotate the gear 70. At the side of the machine, there is a fan 80 with a pipe 81 leading therefrom under the table. The pipe 81 has a plurality 40 of flexible pipes 82 to 88 inclusive connected therewith, and each pipe has a valve as indicated at 89 to determine the quantity of air to be delivered to each of the air boxes 53 to 59.

45 The air under a suitable pressure from the fan 80 passes into the air boxes 53 to 59 inclusive and escapes therefrom under the riffles and at the slots over the tops of the collecting rollers 60, 61 and 62, said rollers 50 being mounted in the air boxes 55, 57 and 59 in such a way as to allow the escape of air above the rollers through slots in the ore supporting table.

55 A sliding gate 90 determines the quantity of material that will be fed to the table.

In operation, a film of ore usually about $\frac{1}{2}$ to 1 inch thick is fed from the hopper 51 over the riffle plates 52. The table is sharply reciprocated to cause the ore to 60 travel down the same. As the ore travels down the table, the air under pressure escapes between the riffles and agitates the ore thereby tending to cause the settlement of the heavy particles while the lighter particles work to the top of the moving ore mass.

The reciprocation of the table causes the topmost ore particles to work down more rapidly than the heavier particles which are retarded by friction on the riffles, and some of which work under the riffles into the 70 concentrate hoppers 53, 54, 56 and 58.

As the heavier particles pass to the collecting rollers, they will drop into the depressions therein, and as said rollers are slowly traveling to the left (Fig. 1) on their 75 upper surfaces they will carry the heavier particles under the riffles and deposit them in the hoppers 55, 57 and 59, the air causing the light particles to be worked up the incline 92 and down the table, said incline 80 causing the air to move in a plane inclined toward the foot of the table. The discharge spouts of each of the receiving hoppers are left open since the quantity of air required to operate the machine is much greater than 85 such a small hole as that of each hopper would interfere with.

As the concentrates pass out of the launders 8 to 14 inclusive, they are delivered in 90 any suitable receptacles.

It will be understood by those skilled in the art that the pipes 82 to 88 inclusive are made sufficiently long and flexible to permit of the necessary adjustment and movement 95 of the table.

It is to be especially noted that the baffle on the discharge side of each roller is provided with an inclined portion 92 up which the air must work the ore, so that the air 100 disturbs substantially every particle thereof in its travel over the table, and at these rollers leaves behind much of the concentrates.

The collecting rollers have been shown as corrugated, but they may be covered with any kind of roughened material which gives 105 a surface suitable to the collection of the fine particles of the heavy material to be concentrated, or they may have a suitable amalgamated surface.

Having thus described our invention, 110 what we claim as new and desire to secure by Letters Patent of the United States is as follows, express reservation being made of permissible modifications.

1. An ore concentrator comprising an inclined table, means to reciprocate the same longitudinally, a plurality of transverse riffles overlapping each other and spaced from each other at their edges to direct air passing thereunder in the line of movement of 115 the table, means to cause air under pressure to pass through the spaces between the riffles, and a plurality of collecting rollers over which the ore passes, and which serve to carry heavy materials caught thereon into 120 the concentrate receiving hoppers.

2. An ore concentrator comprising an inclined table, having a plurality of overlapping riffles spaced from each other, means to adjust the inclination of the table, a plu- 125

rality of collecting rollers carried by the table below the spaces between certain of the riffles and spaced therefrom to form inclined passages over which the ore passes, 5 means to slowly rotate said rollers to deliver heavy particles detained thereon into concentrate receptacles, means to cause a current of air to pass through the several riffle openings to concentrate materials passed 10 thereover.

3. An ore concentrator comprising a reciprocating table, a plurality of substantially horizontal overlapping riffles carried

thereby, means to deliver air under pressure to the table below the riffles, a collecting 15 roller, means to slowly rotate the collecting roller, an incline adjacent the collecting roller up which the air works the ore, and means to drive a current of air upwardly and forwardly through the slot above the 20 compartment in which said collecting roller is installed.

In testimony whereof we have hereunto set our hands this 30th day of July, A. D. 1917.

PETER F. JOHNSON.
ARTHUR L. FIRPO.
